(57) **CLAIM**

The ornamental design for a materials handling vehicle, as shown and described.

DESCRIPTION

FIG. 1 is a perspective view of a materials handling vehicle taken from the left rear of the vehicle, the forks defining the front of the vehicle;

FIG. 2 is a perspective view of the materials handling vehicle taken from the left front thereof;

FIG. 3 is an elevational front view thereof;

FIG. 4 is an elevational back front view thereof;

FIG. 5 is an elevational right side view thereof;

FIG. 6 is an elevational left side view thereof;

FIG. 7 is a top view thereof;

FIG. 8 is a perspective view thereof taken from the left front and showing only claimed subject matter;

FIG. 9 is an elevational front view thereof showing only claimed subject matter; and,

FIG. 10 is a top view thereof showing only claimed subject matter.

The structure shown in broken lines in the figures is included for the purpose of illustrating environment and forms no part of the claimed design.
